[57] CLAIM

The ornamental design for a battery housing for a PCMCIA card modem, as shown and described.

DESCRIPTION

FIG. 1 is a perspective view as seen from the front and upper right of a battery housing for a PCMCIA card modem;

FIG. 2 is a perspective view thereof;

FIG. 3 is a front view thereof;

FIG. 4 is a side view thereof;

FIG. 5 is a rear elevational view thereof;

FIG. 6 is a side view thereof;

FIG. 7 is a top view thereof; and,

FIG. 8 is a bottom plan view thereof.

The broken line showing the connectors, indicator lights and connecting screw are for illustrative purposes only and form no part of the claim design.
